UNITED STATES PATENT OFFICE.

WILLIAM A. V. PORTER, OF NEW YORK, N. Y.

COMBINED SHIPPING AND DISPLAY CARTON.

1,120,238.

Specification of Letters Patent.

Patented Dec. 8, 1914.

Application filed September 12, 1912. Serial No. 719,984.

To all whom it may concern:

Be it known that I, WILLIAM A. V. PORTER, a citizen of the United States, and resident of the borough of Manhattan, in the city and State of New York, have invented a new and useful Combined Shipping and Display Carton, of which the following is a specification.

This invention relates to a combined shipping and display carton, and more specifically to an article of this character which is stamped from blanks of comparatively light, cheap material, such as cardboard; the objects being to provide an article of this kind which is cheap and simple to manufacture, which may be shipped by itself in a flat condition, which may be quickly adjusted into a strong display carton, and which, when in its position for holding the contents, may be assembled with a similar carton to together form a strong and convenient shipping assembly which will adequately protect the contents of the two.

Another object is to provide certain improventers in the form, construction and arrangement of the several parts whereby the above mentioned objects may be effectively carried out.

A practical embodiment of the invention is represented in the accompanying drawings in which,

Figure 1 represents, in front elevation, the carton in its display position with its contents shown therein in dotted lines. Fig. 2 represents a side view of the parts shown in Fig. 1. Fig. 3 represents a top plan view of the same. Fig. 4 represents a vertical central section through the parts shown in Fig. 1, with the contents removed, and Fig. 5 represents, in side elevation, the combination of two filled cartons into a shipping assembly.

The carton proper has a back 1, a bottom 2, sides 3, and front 4. These parts may be stamped from a blank of cardboard or other similar material, with the back, bottom and front composing a continuous body portion, so to speak, and the sides integral with the back but severed from the bottom and front. This blank may be creased at the juncture of the back and bottom, at the juncture of the bottom and front, and at the juncture of the sides and back, for convenience in folding. It will be seen that the back is relatively very high and the front relatively very low; while the sides are sub-

stantially triangular in cross section, so as to extend from the low front well up toward the top of the high back. A tray or support for the contents may also be stamped from similar material in a flat shape, and then creased, folded and secured in the form of two rectangular blocks 5, 6, with an upper corner of the rectangular block 5 adjoining the opposite lower corner of the rectangular block 6; hence providing a stepped support for the cans or other receptacles in which the contents are contained. This tray is secured within the carton by gluing, or fastening in some other convenient manner, the bottom of the block 5 to the bottom 2 of the carton and the back of the block 6 to the back 1 of the carton, as clearly shown in Fig. 4. This tray is collapsible so that when the bottom 2 of the carton is unfolded to lie in the plane of the back 1, the blocks 5 and 6 of the tray will lie flat upon the said back and bottom of the said carton.

The sides 3 of the carton are provided at their lower ends with quadrant shaped flaps 7, which have ears 8 adapted for engagement with slits 9 in the bottom 2 of the carton, for holding the same in its assembled position; while the front 4 has hooked ears 10 fitting within the slits 11 in the said sides 3, for locking the whole together.

It will readily be seen that the carton may be shipped in its unfolded condition with the tray composed of the rectangles 5 and 6 lying flat upon the back and bottom; and that it may be folded by the manufacturer of the contents into the form clearly shown in Fig. 4, the said folding automatically causing the tray 5, 6, to assume a stepped formation for supporting the contents in display location. When it is desired to ship the carton, together with its contents, it is merely necessary to invert one and place it upon a similar one with the upper part of the back of each engaging the low front of the other. In this position, the whole forms a compact rectangular package which may be wrapped and tied in this condition and then shipped. This convenience in shipping is brought about by the general triangular shape of the carton in side elevation, and by the convenient coöperation of the top of the back of each with the low front of the other. The low front and the front of the top of the back may, if desired, contain the name of the manufacturer or advertising or other printed matter.

It will be understood that various changes may be resorted to in the construction, form and arrangement of the several parts without departing from the spirit and scope of my invention; hence I do not wish to limit myself strictly to the structure herein shown and described, but

What I claim is:

1. An article of the character described comprising a back, front, bottom and sides stamped from a single blank, a collapsible tray permanently secured to the back and bottom and arranged to be collapsed flat as the carton is unfolded and to form rectangular stepped blocks when the carton is folded in display position, and means for securing the carton in said display position.
2. An article of the character described comprising a back, front, bottom and sides stamped from a single blank, a collapsible tray permanently secured to the back and bottom and arranged to be automatically collapsed flat as the carton is unfolded and to automatically form rectangular stepped blocks when the carton is folded in display position, and means for securing the carton in said display position.
3. An article of the character described comprising a back, front, bottom and sides, a collapsible tray creased, folded and secured in the form of a plurality of rectangular blocks, with the back of the upper block

secured to the back of the carton and the bottom of the lower block secured to the bottom of the carton, so that when the carton is unfolded, the tray will be collapsed flat and when the carton is folded into display position the tray will form a stepped arrangement of said rectangular blocks, and means for securing the carton in display position.

4. An article of the character described comprising a back, front, bottom and sides, a collapsible tray creased, folded and secured in the form of a plurality of rectangular blocks, with the back of the upper block secured to the back of the carton and the bottom of the lower block secured to the bottom of the carton, so that when the carton is unfolded, the tray will be automatically collapsed flat and when the carton is folded into display position, the tray will automatically form a stepped arrangement of said rectangular blocks, and means for securing the carton in display position.

In testimony, that I claim the foregoing as my invention, I have signed my name in presence of two witnesses, this thirtieth day of July 1912.

WILLIAM A. V. PORTER.
